UNITED STATES PATENT OFFICE.

GILBERT A. ROTH, OF HASTINGS, NEBRASKA.

LUGGAGE CARRIER.

Application filed October 18, 1920. Serial No. 417,613.

To all whom it may concern:

Be it known that I, GILBERT A. ROTH, a citizen of the United States, residing at Hastings, in the county of Adams and State 5 of Nebraska, have invented certain new and useful Improvements in Luggage Carriers, of which the following is a specification.

This invention relates to improvements in luggage carriers of that type devised for 10 detachable connection to the running board of a motor vehicle or the like and capable of adjustment to accommodate articles of various sizes and characters.

The primary object in view is to provide 15 a device of this nature capable of being folded into compact form when not in use, but which may be readily extended and attached in position when desired.

In carrying out the invention I employ 20 supporting standards connected by means of a lazy tong structure—the particular connection between such parts forming an important feature of my invention—and frame members cooperating with the standard 25 so as to form retaining means preventing accidental endwise and lateral displacement of articles carried upon the running board of the vehicle.

For a full understanding of the invention 30 reference is to be had to the following description and accompanying drawings, in which:

Figure 1 is a view in elevation of a device 35 constructed in accordance with my invention and showing the same extended in applied position;

Figure 2 is a sectional view on the line 2—2 of Fig. 1;

Figures 3, 4 and 5 are horizontal sectional 40 views through the connections between the lazy tong structure and the standards, on the planes indicated by the lines 3—3, 4—4 and 5—5, respectively, of Fig. 1;

Figure 6 is an enlarged detail view, partly 45 broken away and showing the strap arrangement used with this device, and,

Figure 7 is an end view of the clamping bracket for the standards.

Throughout the following description and 50 on the several figures of the drawing similar parts are referred to by like reference characters.

Referring to the drawings, 1 designates the running board of a motor vehicle to which 55 the luggage carrier of this invention is designed to be connected in a somewhat con-

ventional manner. The carrier comprises the end standards 2 and the intermediate standard 3, each of which is provided with a U-shaped clamping bracket 4, the upper 60 side of which rests upon the surface of the running board while the underside engages beneath the latter and carries the clamping screw 5 by means of which the standard is securely held in position. The 65 upright part 2' of each supporting standard is formed of strap iron, for example, and bent at its lower end to form a foot 2" which is received between spaced ribs 4' on the upper surface of the clamp 4 and detachably secured to said clamp by means of the cap screw 6. These end standards each 70 embody a frame consisting of the angular piece 7 and the brace piece 8 secured by detachable bolts 9 to the clamping bracket 75 and upright piece 2' as shown most clearly in Fig. 3. The central standard 3 is not provided with this frame 6 necessarily, although such piece may be utilized on all of the standards when desired. The standards 80 2 are connected by means of a lazy tong structure 10 consisting of the usual corresponding levers pivoted together at their ends and centrally, so as to enable the parts to be expanded and contracted in the usual 85 manner.

The lazy tong structure is connected to the end standards at each end by means of a pair of relatively short links 11 which are joined together and pivotally secured to a 90 clip 12 in the plane of the central pivots of the lazy tong levers, the clip 12 passing through a slot 13 in the adjacent end standard as clearly shown in Figs. 3 and 5. The 95 lazy tong structure is connected to the intermediate standard 3 by the common pivot element 14.

It will be noted that the connection of the lazy tong structure to the standards differs from those carriers of conventional 100 form in which it is necessary to secure one of the levers rigidly to the end standard and the other slidably to said standard to enable the parts to be extended and contracted. This simplifies the manufacturing 105 of the device and insures greater facility in operation. Articles of varying sizes or lengths may be disposed upon the running board when the carrier is adjusted so as to be retained thereby. However, it is desirable 110 at times to more positively fix the luggage against displacement, and to this end I have

constructed the carrier of this invention so that a strap member 15 may be attached to engage about the articles disposed upon the running board. For this purpose the outer 5 end of the clamping bracket 4 is formed with an eye 16 to receive the snap hook 17 of the strap, which latter passes preferably through a slot 18 at the top of the standard and secured to an eye bolt 19 detachably fixed 10 to the inner end of the clamping member through the second snap hook 17.

The adjustment and application of the luggage carrier is a simple matter with this 15 type of construction and the articles to be carried are well secured against displacement in travel over rough roads, owing to the specific structure involved in this invention.

Having thus described my invention, what I claim as new and desire to secure by 20 Letters Patent is:—

1. In a luggage carrier of the class described, a lazy-tong structure, a pair of standards each having means at its lower end for clamping it to a running board, and 25 means for pivotally connecting the standards at a single point to the respective extreme ends of said lazy-tong structure, said means comprising a U-shaped clip passing through a slot in the standard and pivoted to the 30 end of the lazy-tong by the pivot member connecting the end bars of the lazy-tong.

2. In a luggage carrier of the type described, a pair of clamping brackets adapted to be secured to the running board of a 35 vehicle and each comprising an arm adapted to rest upon and extend transversely of the upper surface of the running board, a frame detachably secured to each of said brackets and comprising a pair of parallel upright 40 standards attached to said arm near the

ends thereof, a member parallel to said arm and connecting the upper end of one of said standards to the other of said standards and a diagonal brace extending between and connected to said standards, and a lazy-tong structure having its opposite ends connected to the outer standards of the clamping brackets. 45

3. In a luggage carrier of the class described, the combination with a lazy-tong structure, end standards connected therewith to support the same, a standard for the middle portion of the lazy-tong structure, clamping means for each of the standards to secure it to the running board of a vehicle 50 and luggage holding means comprising a strap device connected with the outer end of the middle standard clamping means, also connected with the top of said middle standard and extending to and connected with the inner end of the said middle standard 55 clamping means, forming a bracing means for said middle standard.

4. In a luggage carrier of the class described, a pair of clamping brackets adapted 60 to be secured to the running board of a vehicle and each comprising an arm adapted to rest upon and extend transversely of the upper surface of the running board, each of said arms having lateral flanges, an upright 65 standard for each bracket having a base projecting at right angles thereto and fitting between the flanges of the bracket arm, fastening means passing through the angle portion whereby the standard is prevented 70 from turning with respect to the arm, and a lazy-tong structure having its opposite 75 ends connected to said standards.

In testimony whereof I affix my signature.
GILBERT A. ROTH.
